WOMAN'S LINGERIE

Lenore B. Cooley, New York, N. Y.; The First
National Bank of Santa Fe, Santa Fe, N. Mex.,
executor of said Lenore B. Cooley, deceased

Application December 2, 1946, Serial No. 713,481

4 Claims. (Cl. 2—78)

1
This invention relates to lingerie for women and particularly to a garment having the combined functions of an uplift breast support, a slip and a panty.

One object of the invention is a combined garment of the above indicated character.

A further object of the invention is a novel and improved garment of the above indicated character which is further characterized by the simulated slip effect notwithstanding the panty functioning, by giving the marked freedom of body and leg movement without pull upon the uplift breast support, by its form fit and by the economy with which the garment may be manufactured in quantity production.

A further object of the invention is a garment of the above indicated character which notwithstanding the panty functioning is nonetheless capable of free and easy use for sanitary purposes without the necessity of either the removal of the garment or the unbuttoning or unfastening of the same for these purposes.

Other objects of the invention will hereinafter appear.

For a better understanding of the invention, reference may be had to the accompanying drawings forming a part of this application, wherein:

Fig. 1 is a perspective view of a garment embodying the invention;

Fig. 2 is another perspective view of the garment at a different angle;

Fig. 3 is a diagrammatic view simulating a sectional view along the line 3—3 of Fig. 1;

Fig. 4 is a similar view along the line 4—4 of Fig. 1;

Fig. 4a is a similar view along the line 4a of Fig. 1;

Fig. 5 is a sectional view along the line 5—5 of Fig. 1;

Fig. 6 is a sectional view along the line 6—6 of Fig. 1;

Fig. 7 is a sectional view along the line 7—7 of Fig. 2;

Fig. 8 is an exploded view of the front panels for making the front part of the garment; and

Fig. 9 is a similar view of the panels making up the back of the garment.

Referring to the drawing, my new garment includes an upper part A and a lower part B. The upper part A forms the uplift breast support part which extends down toward but stops short of the waistline C. The lower part B is designed and constructed to have both the functions of a slip and a panty and notwithstanding the panty function is designed and constructed to avoid

undue pull on the upper part A in all body movements. This prevents the undesirable pull upon the breasts and the two parts A and B are designed, constructed and correlated with each other to effect the above purposes and also to effect a form fit about the waist and the upper part of the hips, and also to give the complete simulated slip effect notwithstanding the panty functioning, and also to enable free and easy use for sanitary purposes without the necessity of either removal of the garment or the unbuttoning or unfastening of the same.

The garment is formed of the panels shown in Figs. 8 and 9. The breast uplift part of the garment is formed of three front panels d, e and f, together with a pair of sector shaped parts g and a pair of back panels h. The other or lower part of the garment is formed of the panels j, j' and k, k'. Each of the panels j and k are provided with upper straight line edges 10 which are sewn to the lower straight edge 11 of the panel d to form the front seam 12. The panels j' and k' are provided with similar upper edges 19 which are sewn to the lower straight edges 13 of the panels h to form the seam 14 while the inner straight edges 15 of the panels h are sewn together to form a vertical seam 16 in the back. The panel d is provided with cutouts on the upper part indicated by the curved edges 20 and the cup halves g have corresponding edges 21 which are sewn to the corresponding curved edges 20 to form the seams 22. The panels e and f are provided with inner straight edges 23 which are sewn to corresponding straight edges 24 formed on the part projecting up between the pockets 20, these edges when sewn together forming the seams 25. The panels e and f are also provided with straight edges 26 which are sewn together to form the vertical seam 27. The panel d is widest at the points 28 and from there in the downward direction it is tapered to a width at the bottom approximately equal to the width of the sum of the edges 10 of the lower panels. The tapering side edges of the panel d are indicated at 30. The outer ends of the panels e and f are provided with substantially straight end edges 31 and the lower edges 35, though slightly curved, of the outer ends of the panels are sewn to the straight edges 32 of the panel d with the edges 31 forming a continuation of the edges 30 of the panel d to form seams 33.

The design and construction is such that the edges 31 and 39 form substantially a continuous straight line of the depth of the panels h which is sewn to the outer inclined edges 34 of

the panels *h* to form side seams 35. The upper angular edges of the half cups *g* are sewn to the inner portions of the lower curved edges 36 of the panels *e* and *f* to form seams 37 and cups of the shape illustrated in Fig. 1. The panels *j*, *j'*, *k* and *k'* are provided with outer straight edges 40 and the straight edges 40 of the panels *j* and *j'* are sewn together to form side seams 35' which are continuations of the side seams 35. Each of the panels gradually gets wider from the upper edges until the dotted line 60 is reached, and in the particular embodiment shown the inner tapering edges of these panels are concave curves 42. The tapering portions extend roughly about two-thirds of the depth of the panels while the other one-third is approximately the same width, though slightly wider due to the tapering sides 40, namely the part below the line 41. The inner edges 43 of these lower portions are also formed into a concave curve as shown in the drawings. The panels *j* and *k* are sewn together along their concave curved edges 42 to form the front central seam 44 while the similar curved edges 42 of the panels *j'* and *k'* are sewn together to form the central back seam 45, these seams extending down to the dotted lines 41. The lower portions of the panels *j* and *k* are not sewn together nor are the lower portions of the panels *j'* and *k'* sewn together. Instead the inner lower curved edge 43 of the panel *j* is sewn to the similar edge on the panel *j'* to form the seam 46 while the similar edges of the panels *k* and *k'* are sewn together to form the seam 47, thereby the extreme lower part of the garment is formed into separate parts 48 and 49.

I have indicated *y* measurements in certain of the figures and in the particular embodiment illustrated for a medium sized person, these *y* measurements are in inches and the circumferences of the lower parts 48 and 49 of the garment are roughly 32 inches to 34 inches, due allowance being made for seams. Also these separate parts 48 and 49 are roughly about one-third the depth of the panels and where the bottom of the skirt extends down to the vicinity of the knees the crotch of the wearer is substantially above the crotch of the garment, the crotch of the garment being indicated by the dotted line 60 of Fig. 1 wherein the crotch of the wearer is approximately at the line 61.

The crotch line 60 of the garment is on the upper measurement line 18 1/2*y* in Fig. 9 and this line is approximately half the distance from the line 61 to the knee line, or to the lower measurement line 18 1/2*y* of Fig. 9, and in the particular embodiment shown the crotch line of the garment is slightly less than half the distance from the line 61 to the bottom edge or knee line of the garment.

It is thus apparent that the width of the skirt part of the combined garment not only increases in width to the lower edge but the width is accentuated so as to provide the two separate slip portions 48 and 49 at the extreme bottom of circumferences of from 32 inches to 34 inches, as above described, and in any event should be at least 32 inches in circumference for perfect functioning. Complete freedom of body and leg movement is thereby provided and either of the separate slip portions 48 and 49 may be used for sanitary purposes without the necessity of removal of the garment and with no unbuttoning and unfastening operations required. Also by reason of the particular design and structure

5 shown there is no sagging at any part of the garment, the garment being continuous and flowing in substantially vertical lines without sagging at any part of the circumference thereof.

10 The freedom of movement is moreover obtained without any pull or discomfort upon the bust body part, the crotch line of the garment being so far below the crotch line of the wearer as to obviate any such pull or discomfort, in cooperation with the fullness and particular design of the skirt part both at and below the hips. Moreover the side halves of the lower skirt part formed respectively by the panels *j*, *j'*, *k* and *k'* and the seams 46 and 47 of the separate slip portions 48, 15 49 are in the normal posture completely hidden at both the front and the back as is shown in Fig. 4a, the side halves closing inwardly upon and about and in the front and in the rear of these seams to completely conceal them. The 20 particular design of the upper bust uplift support provides a particularly comfortable yet firm bust support.

25 The garment is provided with any conventional means for fastening and unfastening the upper part for removal and putting on of the garment. This may comprise a conventional zipper along one of the seams 35, 35', preferably the seam on the left side which is not shown in the drawing. This zipper should extend down at least to the waistline C and preferably somewhat lower. Conventional shoulder straps 75 are illustrated for the upper uplift part of the garment. The panels *j*, *j'* and *k* and *k'* are cut on the bias while the part of the garment above these panels is cut with the weave.

30 35 I claim:

1. An uplift slip one-piece lingerie for women comprising an upper bust uplift part and a lower skirt part, the latter being form fitting about the waist and the hips and increasing in width from the waist line to the bottom edge with the extreme lower portion thereof formed into a double slip having a central garment crotch disposed at a substantial distance below the crotch line of the wearer, and the side halves of the lower part being accentuated in width from the hips to the bottom edge to provide the fullness at the sides together with the low garment crotch line required for complete freedom of body movement without pull upon the bust uplift part and to close inwardly from the sides upon and to conceal the division between the double slip portions, said lower skirt part comprising four identical panels, two for the back and two for the front, each of said panels gradually increasing in width from the top to the bottom with both the inner and outer edges tapering in width with respect to each other to a line approximately half the distance from the crotch line of the wearer to the knee line and with the outer edges continuing to taper to the bottom side edges, the inner juxtaposed edges of the panels being formed in concave sections, the upper concave sections passing through the waist line and the crotch line of the wearer and terminating at the crotch line of the garment and the lower section continuing therefrom to the bottom edge with the upper sections of the front panels sewn together and the upper sections of the back panels sewn together while the double slip portions are formed by side front and back portions respectively.

2. An uplift slip one-piece lingerie for women comprising an upper bust uplift part and a lower skirt part, the latter being form fitting about the waist and the hips and increasing in width from

the waist line to the bottom edge, with the extreme lower portion thereof formed into a double slip having a central garment crotch disposed at a substantial distance below the crotch line of the wearer, and the side halves of the lower part being accentuated in width from the hips to the bottom edge to provide the fullness at the sides together with the low garment crotch line required for complete freedom of body movement without pull upon the bust uplift part and to close inwardly from the sides upon and to conceal the division between the double slip portions, the upper bust uplift part being formed of seven separate portions, the front portions comprising separate lower cup pieces for the bust of sector shape and separate upper bust support pieces with a front bodice portion having cut-out parts fitting the sector-shaped bust lower halves and an intermediate upwardly projecting portion therebetween, the side edges of the bodice portion being slightly converging in a downward direction to a lower straight edge and the upper bust support sections having slightly convex lower edges for conforming to the bust support halves and the upper edges of the bodice part, the inner edges of the upper bust support parts having angle edges with the lower edges fastened to corresponding edges of the central upwardly projecting portion of the bodice part and the upper edges being sewn to each other with the outer edges of these upper parts forming continuations of the outer edges of the bodice portion and the back portion of the upper bust supporting part comprising two quadrilateral pieces of irregular shapes with their outer edges conforming to the combined outer edges of the bodice portion and upper bust support portions of the front part with their inner edges sewn together to form a central vertical seam and their upper outer corners projecting into the armpit.

3. An uplift slip one-piece lingerie for women comprising an upper bust uplift part and a lower skirt part, the latter being form fitting about the waist and the hips and increasing in width from the waist line to the bottom edge, with the extreme lower portion thereof formed into a double slip having a central garment crotch disposed at a substantial distance below the crotch line of the wearer, and the side halves of the lower part being accentuated in width from the hips to the bottom edge to provide sufficient fullness at the sides both to give the required fullness for complete freedom of body movement without pull upon the bust uplift part and to close inwardly from the sides upon and to conceal the division between the double slip portions, said lower skirt part comprising four identical panels, two for the back and two for the front, each of said panels gradually increasing in width from the top to the bottom with both the inner and outer edges tapering in width with respect to each other to a line approximately half the distance from the crotch line of the wearer to the knee line and with the outer edges continuing to increase in width, the inner juxtaposed edges of each of the panels being formed in concave sections, the upper concave section terminating at the crotch line of the individual and the lower section continuing therefrom to the bottom edge, the upper bust uplift part being formed of seven separate portions, the front portions comprising separate lower cup pieces for the bust of sector shape and separate

upper bust support pieces with a front bodice portion having cut-out parts fitting the sector-shaped bust lower halves and an intermediate upwardly projecting portion therebetween, the side edges of the bodice portion being slightly converging in a downward direction to a lower straight edge and the upper bust support sections having slightly convex lower edges for conforming to the bust support halves and the upper edges of the bodice part, the inner edges of the upper bust support parts having angle edges with the lower edges fastened to corresponding edges of the central upwardly projecting portion of the bodice part and the upper edges being sewn to each other with the outer edges of these upper parts forming continuations of the outer edges of the bodice portion and the back portion of the upper bust supporting part comprising two quadrilateral pieces of irregular shapes with their outer edges conforming to the combined outer edges of the bodice portion and upper bust support portions of the front part with their inner edges sewn together to form a central vertical seam and their upper outer corners projecting into the armpit.

4. An uplift slip one-piece lingerie for women comprising an upper bust uplift part and a lower skirt part, the latter increasing in width from the waistline to the bottom edge with the extreme lower portion thereof beginning at a point approximately halfway between the crotch and the knees of the wearer formed into a double slip having a central garment crotch disposed at a distance approximately one-half the distance between the crotch and the knees of the wearer and the side halves of the lower part being accentuated in width from the hips to the bottom edge to provide the fullness at the sides, together with the low garment crotch line required for complete freedom of body movement without pull upon the bust uplift part, said double slip having side portions with the inner edges thereof formed in two concave curves the upper portions of which extend to the garment crotch line and the lower portions of which extend from the crotch line to the bottom edge and with the front and back of each side portion sewn together along the lower portions of the concave curved edges and the fronts and backs of the side portions sewn respectively together along the upper portions of the concave edges, with the side portions closing inwardly upon and concealing the crotch line and the division between the double slip portions with either of the latter being usable in the conventional manner without removing or unfastening the garment.
